UNITED STATES PATENT OFFICE

JOHN O. NEIKIRK, OF CHICAGO, ILLINOIS, ASSIGNOR TO RODGER BALLAST CAR CO., OF CHICAGO, ILLINOIS, A CORPORATION OF MAINE

CAR CONSTRUCTION

Application filed April 17, 1931. Serial No. 530,752.

This invention relates to an improved construction for doors of the type employed for discharging lading and is herein illustrated as applied to a discharge door of a ballast car.

5 The car door herein illustrated is adapted for pivotal movement as a whole to discharge lading in one direction and includes in its construction, a secondary door which is pivotally mounted on the door proper and is capable of movement to discharge lading in the opposite direction while the door proper is maintained closed. This type of door is old and well-known and is now in use on certain types of ballast cars.

10 Doors of this type as heretofore constructed, comprise a plurality of spaced transverse braces and one or more longitudinal braces forming the frame of the door proper and in addition, include a strip of sheet material which constitutes the surface of the door proper throughout that portion not occupied by the secondary door. The transverse and longitudinal braces are each attached to the sheet material referred to, whereby the sheet material constitutes the sole means connecting the bracing parts. The secondary door is mounted on one of the longitudinal braces and the door as a whole mounted for pivotal 15 movement by means of the transverse braces whereby in doors so constructed, great dependence is placed upon the intermediate sheet material in assembling the door parts and in maintaining the car door as a unitary structure.

20 It is an object of the present invention to provide a door construction of this general type having all of the features and advantages both in manufacturing requirements and functions in service which is far superior from the standpoint of strength and durability and in which the sheet material providing the door surface is not utilized or depended upon in uniting the parts of the door frame.

25 It is a further object of this invention to provide a door of the character referred to which has a complete, strong and durable frame adapted to be pivotally mounted on the car and to serve as a mounting for the

secondary door, and to which the sheet material constituting the door surface may be attached and supported without in any way constituting a part of the frame itself.

30 It is a further object to produce increased strength and durability in a door which is simple in construction and cheap to manufacture.

35 It is a further object of this invention to provide a door of the type above referred to which will prevent leakage of lading from the car or other container to which it is applied and to thereby eliminate this objection known to exist with doors of this type prior to this invention.

40 These and other objects not specifically enumerated are contemplated in this invention as will readily appear to one skilled in the art as the following description proceeds.

45 In order to understand the nature of this invention, a detailed description of one preferred embodiment thereof will now be given, but it is to be understood that this is merely illustrative of the invention and the invention should not be limited thereby. 50 The scope of the invention may be determined from the appended claims with an understanding of the present disclosure and an appreciation of the advantages which the invention produces therein.

55 The following description refers to the accompanying drawings in which—

60 Figure 1 is a cross sectional view of a portion of a ballast car equipped with doors constructed in accordance with the present invention;

65 Figure 2 is a plan view of a door constructed in accordance with the present invention;

70 Figure 3 is a cross sectional view taken on the line 3—3 of Figure 2 and looking in the direction of the arrows;

75 Figure 4 is a perspective view of the door shown in Figure 3;

80 Figure 5 is an enlarged perspective view of a frame bracket employed in the door construction; and

85 Figure 6 is an enlarged perspective view of a second type of frame bracket employed in the door construction.

90 By referring to the drawings, it will be

noted that the doors of the present invention are illustrated as applied to a ballast or hopper car embodying the usual center sill 10 and side sills 11. The car is also equipped 5 with side walls 12 and shedding surfaces 13 and 14 disposed on opposite sides of the discharge openings 15. The discharge openings are closed by means of doors 20 which are hinged at 16, the movement of which is 10 controlled by the usual apparatus 17 having links attached to the inner edge of the doors by means of brackets 18. It will readily appear that by proper operation of the apparatus 17 the inner ends of the doors will be 15 lowered, permitting them to swing on the hinges 16 with a consequent discharge of the lading. When the doors are opened in this fashion, the lading or ballast will be discharged between the rails of the car track.

20 The construction of the doors 20 is more clearly shown in Figures 2, 3 and 4 and it will be noted that each comprise a series of spaced braces 21 which extend transversely of the door. At the upper ends of the braces, 25 brackets 22 are fastened by means of rivets and serve to mount the hinges by which the door is supported. At the opposite edge of the door, brackets 18 are provided which serve as attachments for the links of the door control mechanism 17. Each of the transverse beams 21 is preferably of inverted U-construction and adjacent the lower edges thereof, longitudinal braces 24 are provided, attached by means of brackets 25 and 25'. The exact 30 formation of bracket 25 is clearly illustrated in Figure 5 and it will be noted that it comprises a back plate 26 having a lower portion secured to the intermediate longitudinal brace 24 and upper wing portions 27 in engagement 35 with the inner walls of the transverse braces and secured thereto by means of rivets or other suitable fastenings.

40 Brackets 25' are used at the ends of transverse braces 21 for connecting the transverse braces directly to the outside longitudinal braces 24. These brackets are substantially U-shaped in form having the upstanding arm slightly angular to fit the interior of the transverse braces 21 to which they are attached by suitable means such as rivets.

45 In the form illustrated, the intermediate longitudinal brace is of channel formation with a bulb bottom flange and the outside longitudinal brace is of Z-formation and by 50 means of the brackets 25 and 25', the longitudinal braces are attached directly to the transverse braces to provide a strong, unitary frame for the car door.

55 In assembling the parts in the manner described, the plate or strip of sheet material 28 is mounted between the transverse and longitudinal braces with openings 29 therethrough for accommodating the brackets 25.

60 The strip of sheet material is then secured 65 by rivets 30 directly to the longitudinal braces.

With this construction, it will readily appear that no reliance is placed on the sheet material for maintaining the door construction intact but, rather, the sheet material is secured to the frame.

70 The inner longitudinal beam 24 is provided with a plurality of hinge brackets 31 to which the secondary door 32 is pivoted, as 75 at 33. Here also, the secondary door is supported directly on the frame without reliance on the sheet metal plate 28. The secondary door 32 may likewise comprise a plurality of transverse braces 35 and a longitudinal angle 80 brace 36 on the outer edge thereof.

85 As shown in Figure 1, the secondary doors are capable of pivotal movement independent of the door proper, which movement is controlled by the chain 37 attached to the under-surface of the door by means of a bracket 38 and bolt 39. The mechanism for controlling the chain is of usual construction and therefore is not illustrated in the drawings.

90 The sheet material constituting the surface 90 for the secondary door 32 is preferably provided with upwardly bent end portions 40 for the usual purpose of directing the flow of lading during discharge and closing the ends of the discharge openings.

95 An important advantage of this invention is the prevention of leakage of lading through the channel openings in the transverse braces 21. In addition to serving as attachments for the transverse and longitudinal braces, the brackets 25 also serve to block off the opening or passage which would ordinarily be provided through the channel space in the braces 21. It will be readily appreciated that when the secondary door 32 is lowered, that the under-side of the channel is exposed, which would permit leakage of material through the channel openings if the bracket 25 were not provided. With the old type of door it was found that leakage of certain types of lading occurred through the channel openings, particularly if the secondary door was prevented from closing tightly against the lower edge of the transverse braces. Such leakage is highly objectionable 100 and constitutes a source of great nuisance particularly with the type of lading which will readily flow beneath the transverse edges and leak out through the channel openings.

105 Although this invention has been illustrated as applied to ballast cars, it is capable of use in any similar installation where discharge doors of this type are provided for hoppers or other containers for lading.

110 The scope of the invention will be apparent 115 from the appended claims.

I claim:

115 1. A door of the character described comprising a frame composed of a plurality of transverse braces, one or more longitudinal 120

130

braces and brackets connecting said transverse and longitudinal braces at their points of intersection, and a plate between said braces secured to said frame, said plate covering only a portion of the area of said frame.

5 2. A door of the character described comprising a frame composed of a plurality of transverse braces, one or more longitudinal braces and brackets connecting said transverse and longitudinal braces at their points of intersection, a plate between said braces secured to said frame, said plate covering only a portion of the area of said frame and a secondary door hinged to said frame serving to cover the remaining portion of the area of said door.

10 3. A door of the character described comprising a frame composed of transverse channel braces and one or more longitudinal braces, and brackets for connecting said transverse and longitudinal braces at their points of intersection, certain of said brackets having portions for interrupting the channel openings in said transverse braces.

15 4. A door of the character described comprising a frame composed of transverse channel braces and one or more longitudinal braces, brackets for connecting said transverse and longitudinal braces at their points of intersection, some of said brackets having portions for interrupting the channel openings in said transverse braces, and a sheet metal plate secured to said frame between said transverse and longitudinal braces.

20 5. A door of the character described comprising a frame composed of transverse channel braces and one or more longitudinal braces, brackets for connecting said transverse and longitudinal braces at their points of intersection, certain of said brackets having portions for interrupting the channel openings in said transverse braces, and a sheet metal plate secured to said frame between said transverse and longitudinal braces having openings therein to accommodate said certain brackets.

25 6. A door of the character described comprising a plurality of transverse channel braces and one or more longitudinal braces, and brackets secured to said braces at their points of intersection, and a plate located between and secured to said braces covering a portion of the area of said door and enclosing a portion of the channel spaces in said transverse braces, certain of said brackets being constructed to block the passage through said enclosed channel space.

30 7. A door of the character described comprising a plurality of transverse channel braces and one or more longitudinal braces, and brackets secured to said braces at their points of intersection, a plate located between and secured to said braces covering a portion of the area of said door and enclosing a portion of the channel space in said

transverse braces, certain of said brackets being constructed to block the passage through said enclosed channel space, and a secondary door pivotally mounted on one of said longitudinal braces.

70

8. A door of the character described comprising a plurality of transverse channel braces and one or more longitudinal braces, and brackets secured to said braces at their points of intersection, a plate located between and secured to said braces covering a portion of the area of said door and enclosing a portion of the channel space in said transverse braces, certain of said brackets being constructed to block the passage through said enclosed channel space, and a secondary door pivotally mounted on one of said longitudinal braces and covering the remaining portion of the area of said door.

75

9. A door of the character described comprising a frame composed of a plurality of spaced transverse channel braces and a pair of spaced longitudinal braces adjacent one end and an intermediate portion of said transverse braces respectively, a plate secured to said braces covering the door area defined by said longitudinal braces, a secondary door pivoted to the intermediate longitudinal brace, and brackets at the points of intersection of said transverse and longitudinal braces providing direct connection therebetween and serving at the location of said intermediate longitudinal brace to block the passage provided by the channel in said transverse braces.

80

100 Signed at Chicago, Illinois, this 14 day of April, 1931.
